ELECTRON BEAM RECORDING APPARATUS
Lewis E. Walkup, Columbus, Ohio, assignor, by mesne assignments, to Xerox Corporation, a corporation of New York

Filed July 15, 1958, Ser. No. 748,655

2 Claims. (Cl. 346—74)

The present invention relates to the art of recording intelligence, and more particularly to a method and apparatus for recording such intelligence by means of a cathode ray or electron beam.

In the high speed recording of intelligence, particularly facsimile or image recording, in many environments the image intelligence is conveyed to a recording station by electrical transmission wherein the image intelligence is carried in the form of varying characteristics of electrical transmission denotative of the intelligence. At the recording station suitable means are provided for transducing the electrical transmission into a visual form and reducing the same to record, permanent or transitory as the needs dictate. In many environments the sensing of the intelligence to be transmitted and the transmission thereof, particularly when sensed electronically or optically, may be effected with extreme rapidity. However, the transducing and reduction of the intelligence to visual and record form frequently imposes serious time limitations on the overall system due to the inability of the recording station to accept the information at the rate capabilities of the sensing and transmission systems.

Electron beam or cathode ray tubes with phosphor screens, due to their ability to respond essentially instantaneously to electrical intelligence applied thereto, have therefore commonly been resorted to as a means for transducing the electrically transmitted intelligence into visual forms. However, the image on the phosphor screens of such tubes is transitory, and does not of itself afford a suitable means for displaying a large amount of intelligence simultaneously, or a memory of intelligence for any significant period of time, particularly if the nature of the transmitted intelligence is continuously varying. Numerous efforts have been directed to recording permanently the transitory images from cathode ray tubes by various optical photographic methods. For many purposes such optical photographic recording is not well adapted, because of the time delay between exposure and developing of the record, the need for wet developing techniques and equipment, and the sensitivity of optical film to cosmic, nuclear, and other radiation. The foregoing drawbacks of optical photographic recording systems are particularly apparent in the environment of military radar, where the equipment may be installed in high altitude reconnaissance craft, and where the need for providing rapid, permanent recording of the radar intelligence is important.

The present invention is directed to recording of intelligence, particularly facsimile or image intelligence, wherein the intelligence is transmitted or presented to the recorder in electrical form. The present invention utilizes a cathode ray or electron beam as the means for transducing the electrical intelligence to record form, thereby taking advantage of the substantially instantaneous response characteristics of such beams. However, rather than utilizing a phosphor screen to convert the intelligence to visual form with the foregoing attendant limitations thereof and disadvantages in the ensuing optical photographic recording of the phosphor image, in accordance with the present invention, the beam is utilized to create an electrostatic image on a moving web, and by xerographic techniques, the electrostatic image may be immediately and continuously developed into a visual image, and, if desired, formed into a permanent record.

2

More particularly, in accordance with the present invention, an electron beam is caused to repetitively traverse a single line of scan at a desired repetition rate. The target scanned by this beam is formed basically from a block of material highly resistive electrically and substantially opaque to (i.e. essentially non-transmissive of) the impinging electron beam. Embedded within the target along the line of scan is a row of electrically conducting pins, each isolated electrically from the others by the target material. With each traverse of the target, the beam deposits an electron charge on the pins. The quantity of charge deposited on each pin may be caused to vary in accordance with variations in the beam current during the traverse, as required by electrical intelligence signals fed to the recording station. While one side of the target is thus repetitively traversed by the electron beam, a web of dielectric sheet material is fed past and in close proximity to the opposite side of the target. Maintaining one side of the web grounded or at a suitable potential difference from the target, the air dielectric between the target and web is disrupted and ionized, resulting in the positive ions traveling to the target, and the negative ions traveling to the web and establishing a corresponding charge thereon. If the web is properly positioned relative to the target, the resultant charge thus induced on the web will constitute a "line" of charge, and the quantity of charge along the length of the line will correspond to the quantity of charge and variations thereof created on the line of pins in the target by the electron beam. Thus, for each traverse of the target by the electron beam, a line of electrostatic charge is induced on the web corresponding to the intelligence fed to the recording station. The rate of movement of the web past the target, and the rate of scan of the target by the electron beam are appropriately correlated to provide on the web a succession of lines of electrostatic charge which taken together denote the image or facsimile intelligence fed to the recording station. This electrostatic image may be continuously developed by xerographic means to provide a visual image of the intelligence, and this image may, if desired, be fixed to a permanent record.

It is accordingly one object of the present invention to provide for the recording of intelligence presented in electrical form.

Another object of the present invention is to provide for the recording of facsimile or image intelligence.

A further object of the present invention is to provide for the recording of intelligence presented in electrical form and transduced to record form by use of an electron beam.

A still further object of the present invention is to provide for the reduction of intelligence carried as a modulation of an electron beam into record form.

An additional object of the present invention is to provide for the reduction of intelligence carried as a modulation of an electron beam into record form by xerographic means and methods.

Other objects and advantages of the present invention will become apparent to those skilled in the art from a consideration of the following detailed description of one exemplary specific embodiment of the present invention had in conjunction with the accompanying drawings, wherein:

FIG. 1 is an exemplary presentation of one embodiment of the present invention, showing a radar system in functional block diagram cooperating with an electron beam recorder illustrated schematically;

FIG. 2 is an enlarged detailed view, partially in section, of the electron beam target used in FIG. 1 and the adjacent image receiving web;

FIG. 3 is an enlarged perspective view of the electron beam target per se;

FIGS. 4-6 are graphs showing the relationship of various parameters of the present invention; and

FIGS. 7 and 8 are schematic showings of a typical xerographic developing system used in conjunction with the electron beam recorder of the present invention.

As previously indicated, one environment in which it is contemplated that the present invention will find important utility is that of recording intelligence derived from a radar scanning system. So far as the present invention is concerned, the particular radar system, or the particular mode of radar scan, is not material. However, in FIG. 1 there is presented schematically an exemplary embodiment of a recorder embodying the principles of the present invention, in conjunction with a functional block diagram of a generalized radar system.

In FIG. 1, the recorder 10 is shown within a dashed line box being fed intelligence from a radar system. The radar system comprises a transmitter 11, feeding an antenna 12. The reflected energy received by the antenna is transmitted through the T-R switch 13 to receiver 14, whose detected output is fed to the recorder 10 through a gating circuit 15. Timer 16 keyed by the radar transmissions triggers a horizontal sweep circuit 17 for the recorder and the gating circuit 15 to program and synchronize the horizontal sweep sequence of the recorder with the application of the received radar intelligence.

The radar received intelligence and horizontal sweep output are applied from circuits 15 and 17 to the recorder 10. The recorder comprises a cathode ray tube 21, whose electron gun and beam control circuits are of conventional design. These include a cathode 22, control grid 23, first and second anodes 24 and 25, electrostatic horizontal deflection plates 26, electrostatic vertical deflection plates 27, and intensifying ring 28, all operated in a conventional manner from a suitable power supply generally indicated as 29. The output of the radar receiver 14 as passed by the gating circuit 15 is applied to the control grid of the electron gun, and thus controls the electron beam current. The output of the horizontal sweep circuit 17 is applied across the horizontal beam deflection plates 26, and thus controls the electron beam scan pattern and sequence across the target of the cathode ray tube. It may be mentioned at this time that the vertical beam deflection plates 27 are adjustably set to a selected bias value. The reason for this is, as will become apparent subsequently, that the present recorder operates on only one horizontal line or vertical position for the electron beam.

Considering the general operation of the apparatus thus far described, for each scan cycle of the radar system, the reflected energy denoting that scan cycle is passed by the gate 15 and applied to the control grid 23 of the electron gun in tube 21. Simultaneously and in timed relation thereto, the electron beam is caused to effect one scan across the tube target, generally denoted by numeral 31 in tube face 46, the vertical deflection plates of the tube being biased to this vertical beam angle. The intelligence contained in the reflected radar energy, which may for example be in the time of receiving the reflected energy or in the intensity thereof, or both, is utilized to modulate the current in the electron beam of tube 21 through operation of the control grid 23. Thus, as determined by the radar intelligence, a varying quantity of charge, or a varying charge pattern, is established along the horizontal scan line of the target 31 for each scan cycle of the electron beam. As will be more fully explained subsequently, from this charge pattern applied to the target 31, a corresponding line of charge pattern is induced on that portion of the web 32 immediately adjacent the target. Thus, as each successive line of intelligence, so to speak, is obtained from the radar system, it is accordingly transduced onto successive lines of the web 32 as the latter is advanced past the target from supply roll 33 to take-up roll 34. At 35 the electrostatic charge pattern thus induced on

web 32 is developed by usual xerographic means into a visual image, thereby providing a visual facsimile presentation and record of the information, such as the topography, scanned by the radar system.

5 The electron beam target per se 31 is shown in FIG. 3 as a rectangular block of material having a high electrical resistance, and which is substantially impervious to the electrons impinged thereon by the electron beam. The target may be formed, for example, from polymethyl 10 methacrylate or glass, or other high resistance material having a resistivity of at least 10^{12} ohm-cm. Embedded within the target material 31 is a line of pins 44, each extending transversely through the target and lying in the plane 40 indicated in dotted lines. The pins are 15 formed from a conducting material such as tungsten wire. One end of each pin 44 is formed flush with the surface 47 of target 31, while the other end extends from the surface 48, and for reasons subsequently explained is bent down to provide each pin with a tail 45.

20 The effect of secondary emission from the pins depends on the secondary emission ratio of the pins themselves, that is, the average number of secondary electrons produced by each primary electron. If this ratio is less than unity, the result of the secondary emission is to reduce the 25 effective electron current to the pins. If however, the ratio is larger than unity, the consequence is a reversal of the current to the pins, with the result that the pins will become positively charged rather than negatively charged. Certain compounds, generally suitably activated 30 oxides such as cesium-oxygen-silver compounds, produce electron yields of from 4 to 6. To obtain an effective charge multiplication in the pins utilizing this effect (as by coating the portions of the pins receiving the primary 35 electron beam with a cesium-oxygen-silver compound) requires the control of a number of factors such as relatively low primary electron potentials, the angle of incidence of the primary electrons to the target surface, etc.

As shown in FIG. 2, the target 31 is sealed in the face 46 of cathode ray tube 21, with the flush ends of pins 44 on the exterior of the tube, and the bent ends, or tails, 45 on the interior of the tube. Electrons from the cathode ray tube beam designated by arrows 41 impinge upon the tails 45 and are thus collected on the pins 44. Immediately opposite and exterior of the target 31 there is positioned a mandrel 43 of electrical conducting material which may be grounded as shown, or have a positive potential applied thereto. Web 32 of dielectric material, such as polyethylene terephthalate aluminized on the surface contacting mandrel 43, is passed over the tip 50 of the mandrel 43 in intimate electrical contact therewith.

The electron charges accumulated on the pins 44 set up electrostatic fields between the pins and the mandrel 43, and when the potentials of these fields are of sufficient 55 magnitude, the air in the space 49 between pins 44 and web 32 is ionized. The positive ions are attracted to the pins, while the negative ions are attracted to the web. The resultant electrostatic charge thus induced on any spot on web 32 is a function of the charge present on that pin immediately opposite the spot on web 32 under consideration. Since the charge present on any particular pin 44 is a function of the electron beam current impinged thereon, and this in turn is a function of the radar intelligence obtained from the radar system, it is apparent that 60 for each cycle of scan along target 31 by beam 41, a line of intelligence is induced across the web, with the variations of intelligence within that line being denoted by the variations in charge induced thereon.

As previously mentioned, the pins 44 are provided with 65 depending tails 45. The purpose of the tails is to eliminate the need for critical adjustment of the vertical deflection angle of the electron beam, since the beam may impinge upon any portion of the tails rather than be required to be precisely adjusted to the line of the pins.

The foregoing description of the present invention sets

forth the general structure and operational characteristics thereof. However, practice has shown that many other relationships and parameters of the system must be satisfied before the system will function as a facsimile recorder. One critical parameter is the pin potential that must be obtained before a xerographically developable charge will be induced on the pickup web 32. This may be calculated by first deriving an expression for the potential, E, of the pin with respect to ground, required before the air gap 49 between the pin and pickup web breaks down:

$$E = \frac{Q}{C} \quad (1)$$

where

E is the pin potential with respect to ground in volts, Q is accumulated charge on the pin in coulombs, and C is the pin capacitance to ground in farads.

Since

$$C = \frac{C_1 C_2}{C_1 + C_2} \quad (2)$$

where

C₁ is the capacitance of the area of the pickup sheet adjacent to the pin, in farads, and

C₂ is the capacitance of the pin to the pickup sheet in farads;

therefore,

$$E = \frac{Q(C_1 + C_2)}{C_1 C_2} \quad (3)$$

This potential, E, from pin to ground consists of two components, one, E₂, is across the air gap from the pin to the surface of the pickup sheet, and the second is across the pickup web. E₂ can be expressed as:

$$E_2 = \frac{Q}{C_2} \quad (4)$$

where E₂ is the potential across the air gap in volts.

The potential across the whole system can therefore be expressed as:

$$E = E_2 \frac{C_1 + C_2}{C_1} \quad (5)$$

If E₂ is the breakdown potential of air for the air gap thickness used, then E is that potential which, when applied to the pin, will just initiate electrical breakdown in the air gap and, hence, cause charge induction on the pickup web in response to pin potential. Thus, this potential always will be greater than that necessary to break down the air gap alone, and assuming no electrical leakage, will depend on the capacitance of the pins and the pickup web. Equation 5 is approximate, in that spreading of the electric field is neglected. However, experimental results have shown this equation to be quite accurate. Based on Equation 5, FIG. 4 shows graphically the relationship of air gap distance 49 to pin potential required for charge induction on the pickup web, for various thicknesses of polyethylene terephthalate webs. As a generalization from said graph, it should be noted that for each thickness of pickup web there is a minimum value of charge induction potential occurring in the air gap range of from about 10 μ to about 30 μ .

In FIG. 5 there is presented the experimentally ascertained relationship of minimum pin potential to air gap for obtaining an induced xerographically developable charge on a pickup web of polyethylene terephthalate having a thickness of 35 μ . It may be observed from this graph that air gaps in the range of from 6 μ to 25 μ require a pin potential of from about 600 volts to 800 volts. These ranges represent the preferred operating ranges of the present invention. It has been found that air gaps greater than 50 μ are unsuitable for the purposes of the

present invention because of poor image quality generally produced.

FIG. 6 presents a graph of image width as a function of pin potential and air gap distance for three air gap distances, 6 μ , 12 μ , and 25 μ , using pins having a diameter of 25 μ . Upper and lower limits of the measured image widths are presented, as well as the range common to all three air gaps. The values given are those obtained with the mandrel and pickup web adjusted to optimum obtainable lateral alignment with the line of pins in the tube. From this graph one may observe that a resolution of 10 lines/mm. is obtainable, and such is considered an important minimum limitation upon good quality facsimile reproduction. Image width increases with increasing pin potential. Image width appears to be independent of air gap in the ranges of 6 μ to 25 μ . For gaps greater than 25 μ , however, image width increases rapidly with increased air gap.

The matter of lateral alignment of the mandrel and pickup web with the row of pins in the tube is mentioned above. The tolerance with respect to this parameter has been found to be about 100 μ at an air gap of 6 μ , increasing to a maximum of 200 μ with a 12 μ air gap, and decreasing again to about 100 μ with an air gap of 25 μ . By tolerance herein is meant the lateral range over which image induction is had on the web at the minimum transfer potential as shown in FIG. 5. Although the greatest tolerance in lateral positioning is had with an air gap of about 12 μ , it is preferred to utilize a 25 μ air gap, which would be less difficult to maintain than 12 μ , and accept the reduced tolerance in lateral alignment.

Accordingly, it may be summarized that to render the invention herein described suitable for facsimile recording, the following operational characteristics must be met: The air gap between pins and pickup web must be less than 50 μ , and preferably between 6 μ and 25 μ . The pin potential must be at least in the range of from about 600 volts at a 6 μ air gap to about 900 volts at a 50 μ air gap, when using a pickup web having the capacitance of 35 μ thick polyethylene terephthalate (polyethylene terephthalate has a dielectric constant of approximately 3.5), the voltages generally increasing with increasing air gap, and of from about 600 volts to about 800 volts in the preferred air gap range of 6 μ to 25 μ . For maximum line resolution, the pin potential should be kept close to the minimum value at which xerographically developable charge induction occurs.

It has been shown that with tungsten pins of 25 μ in diameter spaced from each other 50 to 125 μ on centers, embedded in a polymethyl methacrylate block, line resolution of better than 10 lines/mm. is obtainable, if the foregoing parameters are adhered to. Of course, the electron beam scanning the target must have a diameter at the target of less than the line resolution sought. Electron beam guns are commercially available with beam diameters substantially less than 0.1 mm. In order to obtain the pin potentials required, the electron beam gun should also be capable of an acceleration potential of 5 to 10 kv., and an electron beam current of 1 μ ampere. These requirements together with a beam spot of less than 0.1 mm. are available in a Type 5F electron gun.

With reference to FIGS. 7 and 8, there is presented the principles of, and an exemplary mechanism for, transforming into visual form the electrostatic image of intelligence induced on web 32 by operation of the electron beam. The thin electrically insulating web 32 drawn from supply roll 33 may be a plastic film, such as polyethylene terephthalate, polystyrene, cellulose acetate, ethyl cellulose, or like sheet material of good insulating properties, and preferably of the order of one or two mils thick; or it may be of paper coated on the working surface with one of these plastics, or with a wax; or in some instances thoroughly dry paper or cellophane can be used. As the web 32 is drawn from its roll 33, it first passes through a preliminary charging device 51, where the web is brought to a uniform state of electrostatic

charge. From the preliminary charger, the web is then passed between the electron beam target of tube 21 adjacent one surface of the web, and the ground mandrel 43 adjacent the opposite surface, where an electrostatic charge pattern depicting the intelligence is induced on the web. The web then enters a development mechanism 35, where the electrostatic charge pattern on the web is rendered visible by the selective application of a finely divided material, such as electroscopic powder, or a liquid ink, or like material. As the web emerges from the developer, the intelligence carried thereon is visually intelligible. Where a permanent record of the intelligence is desired, the web is then passed to fuser 57, where the powder is permanently fused to the web, or the ink is dried. As is apparent, if only a transitory presentation of the intelligence is desired, the fuser may be omitted, and instead of a fresh web supply roll, the web may be in the form of an endless belt, with means interposed between the developer 35 and the preliminary charger 51, on the return side, to clean the intelligence off the web.

The purpose of preliminary charger 51 is to establish over the web a uniform electrostatic charge preparatory to receiving the intelligence charge pattern. Charger 51 comprises a housing within which is located an electrode 52 coated with a radioactive source of ionizing particles, such as a polonium layer, which faces one surface of the web. The opposite surface of the web 15 is contacted by a ground plate 54, while voltage source 53 as tapped by a potentiometer 55 is connected to the electrode 52. The potentiometer 55 is center-tapped to ground, and the battery of voltage source 53 is preferably one hundred to several hundred volts. By varying the potentiometer setting, one can thus establish a field of either polarity and of adjustable intensity between electrode 52 and web 32.

The alpha or other ionizing particles emitted by the radioactive layer on electrode 52 produce ionization of the air in the chamber 51 into negative and positive ions, and these ions migrate in opposite directions, depending on their polarity, under the influence of the electrostatic field existing between electrode 52 and plate 54. As ions of one polarity deposit their charge on web 32, the field becomes altered by the charge on the web until a state of equilibrium is reached, in which the potential of the web surface is equal to the potential applied to electrode 52 by the potentiometer. Whether a small positive potential or negative potential is applied to the web, as controlled by the setting of the potentiometer tap, depends on factors subsequently considered. In some instances the electrode 52 may be held at ground potential, in which case the device merely serves to remove incidentally acquired electrostatic charges from the web in preparation for receiving the electrostatic intelligence charge pattern. Instead of a radioactive source of ionizing particles, the electrostatic charges may be supplied by corona emission as disclosed, for example, in U.S. 2,777,957 to L. E. Walkup. With the web 32 thus prepared, it is passed between the electron beam target of tube 21 and mandrel 43 to receive the intelligence charge pattern, as afore-described. The web 32 carrying the intelligence in electrostatic charge form, passes from intelligence transducing station into the developer 35, shown schematically in FIG. 5. This device comprises a pair of rollers 60 and 65. Roller 60 includes a central bearing shaft 64 carrying a pair of axially spaced disks 62 over which the web edge peripheries pass. Flanges 61 confine the web in place on disks 62. The web and disks 62 thus form a hopper in which a supply of electroscopic powder 63 is contained. It is preferable, although not necessary, that the powder 63 be charged by triboelectric or other means to carry an electrostatic charge opposite from that induced on the web at the transducing station. The powder adheres in the charged areas to produce a visible presentation of the intelligence carried by the web. As the powder 63 is tumbled over the web 32, if the initial preliminary charg-

ing of the web at 51 were of a polarity opposite from that obtained at the tube 21, then this background charge on the web would be of the same polarity as the charged powder, and would assist in repelling the developer powder from this background area. After being developed, the web passes from roller 60 up over roller 65, and down into fuser 57. In fuser 57 the web passes about roller 58 where it is heated to a temperature sufficient to fuse the developer powder to the web, or, if ink were used as the developer, to dry the ink thereon, thus forming a permanent visual and directly readable record of the intelligence transduced at tube 21. The web may then pass between suitable drive rolls such as 89.

The described method of rendering the pattern of electrostatic charges visible, i.e., developing the image, is known as "loop" development. This system is disclosed in U.S. Patent 2,761,416 to C. F. Carlson. The method of development is not critical in the instant invention and other methods for contacting electrostatically charged marking particles with the electrostatic image may be used. Thus a spray of electrostatically charged liquid droplets or dry powder particles, as disclosed in U.S. Patent 2,784,109 to L. E. Walkup may be used or magnetic brush development described in U.S. Patent 2,791,949 to Simmons and Saul are all operable. A powder cloud development apparatus particularly suited for use as developer 35 in the present system is the device known as a slot development apparatus more particularly described in U.S. 2,815,734 to C. F. Carlson. Devices such as that described in said U.S. 2,815,734 have been made wherein the development system is limited to $\frac{1}{4}$ inch, thereby making possible almost instantaneous viewing of the developed image. The choice of a particular developing process or apparatus would obviously be dependent on the combination and design limitations imposed in assembling the machine for a particular operation.

Similarly, the means of permanently affixing the powder image to the backing material is not critical in the instant invention. Thus, if no permanent image is desired, after examination of the roll, the loosely adhering powder image may be wiped off as by swabbing with cotton or a rapidly rotating fur brush and the roll reused. If a permanent record is desired, the powder particles may be rendered adherent to the backing material by heating, as previously disclosed herein, by contacting the powder-bearing sheet with the vapors of a solvent for the marking particles or for a resin coating on the image receiving member as disclosed for example in U.S. Patent 2,776,907 to C. F. Carlson. Where liquid droplets are used, absorption of the liquid into the capillaries of the backing member or an evaporation of the liquid would serve to affix the image to the image receiving sheet. Other means of affixing the powder image, as by the use of pressure, by spraying with a fixative liquid, etc., also may be used if desired. If desired the image may be transferred from dielectric web 32 to an image support member as paper and affixed thereto with web 32 being recycled in the image-forming process.

The possibility of using a pin tube for direct electron beam recording has long been obvious to those skilled in the art. Heretofore, however, it has not been possible to obtain dependable operation with high resolution. Thus it has been suggested to lead the image receiving web in contact with the pins and form the image by electrolysis (using an electro-sensitive paper as Teledeltos paper) giving very low image densities and poor resolution or by electrostatics also giving very low resolution (in the laboratory two lines per mm. resolution were obtained in this manner while using the instant invention 10-15 lines per mm. are easily obtained). It has also been suggested to space the image receiving web from the pins, but under conditions of voltage and spacing causing poor resolution or undependable operation, or both. The instant invention for the first time presents the critical interrelationship

between potential and spacing required for high resolution and dependable operation.

From the foregoing detailed exemplary description of the present invention, it will be appreciated that there is presented a method and means for recording electrically transmitted intelligence, utilizing an electron beam as the means of transducing the electrical form of intelligence onto record form, in such manner as the record may be rendered visual and permanent, if desired, by usual xerographic techniques. Although the present recording technique has been illustrated in conjunction with a radar system for sensing and presenting the intelligence to be recorded, such is presented only as exemplary of one field of use for the present invention. As will be apparent to those skilled in the art, the present invention may be utilized generally in the field of recording, and it is not intended that the foregoing description shall be interpreted as limiting the scope of the present invention to radar. Also, other variations, modifications and adaptations of the present invention will be apparent to those skilled in the art, and such as come within the spirit and scope of the appended claims are considered to be embraced by the present invention.

I claim:

1. A cathode ray device comprising an envelope, an electron gun in said envelope for projecting a beam of electrons, and a target in the face of said envelope to which said beam is directed, said target comprising a block of material essentially non-transmissive of electrons impinged thereon by said beam and having a high electrical resistance, a plurality of electrically conducting pins embedded in said block extending through said

25

30

block from the interior of said envelope to the exterior thereof and arranged in a line, the ends of said pins extending to the interior of said envelope having portions extending exteriorly of said block and angularly disposed relative to the portions thereof embedded in said block, said angularly disposed portions being substantially parallel to each other, whereby said electron beam may scan said pins by traversing said angularly disposed portions, means to modulate said electron beam and an electrically conductive mandrel adjacent said pins but spaced therefrom and adapted to support a web of electrically insulating material in spaced parallel relation to said pins at a distance of from about 6 to about 50 microns, said mandrel being in electrical circuit with said gun whereby a charge established on said pins by scanning thereof by said beam will disrupt the air between said pins and web and thereby induce an electrostatic charge on said web in accordance with the electron charge carried by said pins.

20 2. A device as set forth in claim 1 wherein said electron beam is modulated by varying the current thereof.
